CIRCUIT BREAKER

Albert R. Cellerini, Beaver, Pa., assignor to Westinghouse Electric Corporation, East Pittsburgh, Pa., a corporation of Pennsylvania

Application November 23, 1951, Serial No. 257,812

10 Claims. (Cl. 200—116)

1

This invention relates to circuit breakers and more particularly to circuit breakers for controlling lighting and moderate power circuits.

An object of the invention is to provide a circuit breaker embodying an improved thermally responsive trip device wherein the thermally responsive element also compensates for changes in ambient temperatures.

Another object of the invention is to provide a circuit breaker embodying an improved thermally responsive trip device comprising a single thermally responsive tripping element, a portion of which acts to compensate the trip device for changes in ambient temperatures.

A further object of the invention is to provide a circuit breaker embodying an improved trip device comprising a tripping bimetal element formed from a single strip of bimetallic material having a portion which acts to compensate the trip device for changes in ambient temperatures.

The novel features that are considered characteristic of the invention are set forth in particular in the appended claims. The invention itself, however, both as to structure and operation, together with additional objects and advantages thereof, will be best understood from the following detailed description of several modifications thereof when read in conjunction with the accompanying drawing.

In said drawing:

Figure 1 is a side elevational view, partly in section, of a circuit breaker embodying the principles of the invention;

Fig. 2 is an enlarged fragmentary elevational view of the trip device.

Fig. 3 is an enlarged fragmentary view showing a modification of the trip device.

Referring to Fig. 1 of the drawing, the circuit breaker comprises generally a base 11 and a cover 13, both of molded insulating material, a stationary contact 15, a movable contact 17, an operating mechanism 19 and a trip device 21. The stationary contact 15 is mounted on the inner end of a strip 23 of conducting material, to the other end of which is secured a terminal connector 25.

The movable contact 17 is carried on the free end of a spring contact arm 27 which is secured to a U-shaped movable switch member 29. The movable contact 17 is electrically connected by means of a flexible conductor 31 to the current responsive trip means of the trip device 21 which will hereinafter be described. The current responsive trip means is, in turn, connected to a conducting strip 33 connected at its outer end 55 to a terminal connector 35.

2

The movable switch member 29 is pivotally mounted on a pin 37 supported in the side walls of a generally U-shaped frame 39 secured to the base 11 of the breaker housing. A stop pin 41 supported between the sides of the frame 39 cooperates with projections 43 on the U-shaped switch member 29 to limit the opening movement of the switch member.

The operating mechanism 19 is mounted in the frame 39 and comprises a U-shaped operating lever 45 having its legs pivoted on pivot members 47 struck out from the frame 39, a releasable carrier lever 49 pivoted on a pin 51 in the frame 39, a pair of toggle links 55 and 57 and overcenter springs 59 (only one being shown). The toggle links 55 and 57 are pivotally connected together by means of a knee pivot pin 61. The inner toggle link 55 is pivotally connected by means of a pin 63 to U-shaped switch member 29 and the toggle link 57 is pivotally connected at its outer end by means of a pin 65 to the releasable carrier lever 49. The overcenter springs 59 have their outer ends connected to the right portion of the U-shaped operating lever 45, and their inner ends are connected to the knee pivot pin 61 of the toggle 55—57. An operating handle 67 of molded insulating material is secured to the outer end of the operating lever 45 and is provided with a handle portion which extends through an opening 69 in the cover 13. The operating handle is also provided with an arcuate portion 71 which serves to substantially close the opening 69 in all positions of the handle. Lugs 73 struck out from the sides of the frame 39 serve as stops to limit the opening and closing movement of the operating lever 45.

The breaker contacts are opened manually by clockwise movement of the operating handle from the position in which it is shown in Fig. 1. This movement carries the line of action of the overcenter springs 59 across to the right of the pivot pin 65 whereupon the force of the springs causes collapse of the toggle 55—57, thereby moving the movable contact to the open position with a snap action. The contacts are closed by counterclockwise movement of the handle back to the Fig. 1 position. This moves the line of action of the overcenter springs 59 across to the left of the pivot pin 65, at which time the springs actuate the toggle 55—57 to its extended overset positions shown, thereby moving the movable contact to the closed position with a snap action.

The trip device 21 comprises a bimetal element 75 having a mounting foot 77 rigidly secured by means of a screw 79 to the base 11 of the housing. A main portion 81 of the bimetal element

15 extends at right angles to the mounting foot 17 and the outer or free end thereof is looped as at 83 so that a portion 85 of the bimetal element extends back substantially parallel to the main body 81 but spaced therefrom. The portion 85 of the bimetal element has secured thereto a latch member 87 which engages a latch 89 secured to but insulated from the carrier lever 49 to releasably restrain the carrier lever in the position shown. A flexible conductor 91 connects the bimetal element 75 at the point approximately midway between the mounting foot 17 and the end of the portion 85 to the conducting strip 33.

The high expansion side of the main body 81 of the bimetal element is on the left (Fig. 1), on the inside of the loop 83 and on the right of the portion 85. Only that portion of the main body 81 of the bimetal element between mounting member and the point of connection of the flexible conductor 91 is traversed by the current of the circuit. The loop 83 and the portion 85 of the bimetal element are responsive to the temperature of the surrounding medium. An increase in the temperature of the surrounding medium, which would cause the main body 81 of the bimetal element to bend toward the right, would cause the loop 83 to tend to straighten out and the portion 85 to bend toward the left, thus maintaining a substantially constant latch overlap. If the temperature of the surrounding medium decreases, the main body 81 of the bimetal element will bend toward the left, whereas the loop 83 will tend to close and the portion 85 of the bimetal element will bend toward the right maintaining the proper overlap of the latch elements 87—89.

The lower portion of the bimetal element below the flexible conductor 91 is heated in response to the flow of overload currents therethrough, and, when heated a predetermined amount, bends toward the right moving the loop 83 and the portion 85 therewith to disengage the latch member 87 from the latch 89 to release the carrier lever 49. Upon release of the carrier lever 49, the force of the overcenter springs 59 rotates the carrier counterclockwise about its pivot 51, moving the pivot 65 across to the left of the overcenter springs 59, whereupon the springs cause collapse of the toggle 55—57 and opening of the contacts.

Before the breaker can be closed following an automatic opening operation, it is necessary to reset and relatch the carrier lever 49. This is accomplished by movement of handle and the operating lever 45 to the full clockwise position. During this movement, a projection 93 on the operating lever 45 engages a shoulder on the carrier lever 49 and rotates the carrier lever in a clockwise direction. Near the end of the clockwise movement of the carrier lever, the latch 89 wipes by the latch member 87 slightly bending the bimetal element which thereafter resumes its latching position. The contacts are then closed in the previously described manner by counterclockwise movement of the operating lever.

According to the modification illustrated in Fig. 3, a bimetal element 94 is rigidly mounted by means of a screw 95 to the base 11 of the housing. The free end of the bimetal element is looped as at 97 so that a portion 99 thereof extends back substantially parallel to the main body 101 of the bimetal element. The portion 99 of the bimetal element has secured thereto a latch member 103 which engages the latch 89

on the carrier lever 49 and releasably restrains the carrier lever 49 (Fig. 1). The bimetal element 94 is connected to the conducting strip 33 by a flexible conductor 105 and a flexible conductor 107 connects the end of the portion 99 of the bimetal element to the movable contact 17.

The high expansion side of the bimetal element 94 is on the right of the main body 101 thereof, on the outside of the looped portion 97 and on the left of the portion 99. That portion of the bimetal element between the points of connection of the flexible conductors 105 and 107 is heated in response to the current flow therethrough. That portion of the bimetal element 93 below the point of connection of the flexible conductor 105 is responsive to the temperature of the surrounding medium. A rise in the temperature of the surrounding medium would cause the main body 101 of the bimetal element to bend toward the left, would cause the loop portion 97 to contract and the portion 99 to bend toward the right, thus maintaining a substantially constant latch overlap. If the temperature of the surrounding medium decreases, the portions of the bimetal will bend in the opposite directions and maintain the proper overlap of the latch elements 103—89.

The portion of the bimetal element between the points of connection of the flexible conductors 105 and 107 is heated in response to the flow of overload currents therethrough, and when heated a predetermined amount the loop portion 97 contracts and the portion 99 bends toward the right to disengage the latch member 103 from the latch 89 and release the carrier lever 49 (Fig. 1). This effects automatic opening of the breaker in the previously described manner.

The invention provides a circuit breaker having a novel thermally responsive trip device comprising a thermal trip means formed from a single strip of bimetallic material, one portion of which comprises the tripping element and another portion serves to compensate the tripping portion of the thermal element for changes in ambient temperatures.

While the invention has been disclosed in accordance with the provisions of the patent statutes, it is to be understood that various changes and modifications may be made in the structural details thereof without departing from the spirit of the invention.

I claim as my invention:

1. In a circuit breaker comprising relatively movable contact means and releasable operating means therefor, a trip device comprising a single bimetal element having one end supported and the other end free, said bimetal element having a reverse bend about a transverse axis parallel to its faces to form a loop, said bimetal element having the high expansion side on the inside of said loop, means electrically connecting only a portion of one leg of said bimetal element to be traversed by current of the circuit, latch means on the other leg of said bimetal element releasably restraining said operating means, the legs of said bimetal element moving in opposite directions in response to changes in ambient temperature to compensate said trip device for changes in ambient temperature, and thermal bending of said bimetal element in response to overload currents causing said latch means to release said operating means and automatic opening of said contact means.

2. In a circuit breaker comprising relatively movable contact means and operating means re-

leasable to effect automatic opening of said contact means, a trip device comprising a single U-shaped bimetal element normally restraining said operating means, said bimetal element having legs of unequal length, said bimetal element being connected in the circuit of the breaker so that only a portion of the longer leg is heated by the current of the circuit, the high and low expansion sides of said bimetal element being so arranged that the legs of said bimetal element move relative to each other in response to changes of ambient temperature to compensate said trip device, and thermal bending of said bimetal element when heated in response to overload currents causing release of said operating means and opening of said contact means.

3. A circuit breaker comprising separable contact means and operating means releasable to cause separation of said contact means, a trip device for effecting release of said operating means comprising a single bimetal element having a return bend about a transverse axis parallel to its faces to form a loop having legs of unequal length, the high expansion side of said bimetal element being on the inside of said loop, support means supporting the longer leg of said bimetal element, latch means on the shorter leg of said bimetal element cooperating with said operating means to releasably restrain said operating means, means connecting said longer leg in the circuit of the breaker so that a portion of said longer leg is traversed by the current of the circuit to be heated thereby, the current traversed portion of said bimetal element when heated by overload currents bending and bodily moving said shorter leg in a direction to disengage said latch means and release said operating means, the proportions of said legs and said loop being such that said legs deflect relative to each other in response to changes in ambient temperature to maintain a substantially constant latch overlap to thereby compensate said trip device for changes in ambient temperature.

4. A circuit breaker comprising means releasable to cause automatic opening of said breaker, a trip device comprising a bimetal element formed from a single strip of bimetallic material and having a reverse bend about a transverse axis parallel to its faces to form a loop, said bimetal element having the high expansion side on the inside of said loop, means connecting a portion only of said bimetal element in the circuit of the breaker to be heated by the current of the circuit, means securing one leg of said bimetal to a fixed member, means at the other leg of said bimetal element for initiating release of said releasable means, and the legs of said bimetal element moving in opposite directions in response to changes in ambient temperature to compensate said trip device for changes in ambient temperature.

5. A circuit breaker comprising means releasable to cause automatic opening of said breaker, a trip device comprising a bimetal element formed from a single strip of bimetallic material having a reverse bend about a transverse axis parallel to its faces to form a loop, said bimetal element having the high expansion side on the inside of said loop, means supporting one leg of said bimetal element, means at the other leg of said bimetal element for effecting release of said releasable means, means connecting a portion only of said bimetal in the circuit of the breaker to be heated by the current in the circuit, said

heated portion of said bimetal element when heated by overload currents deflecting and moving said loop to effect release of said releasable means, and the legs of said bimetal element moving relative to each other in response to changes in ambient temperature to compensate said trip device.

6. In a circuit breaker having relatively movable contact means and operating means releasable to effect automatic opening of said contact means, a trip device comprising a single U-shaped bimetal element normally restraining said operating means, said bimetal element having legs of unequal length, said bimetal element being electrically connected in the circuit of the breaker so that only a portion thereof is heated by the current of the circuit, the high and low expansion sides of said bimetal element being so arranged that the legs of said bimetal element move relative to each other in response to changes in ambient temperature to compensate said trip device, and thermal bending of said bimetal element when heated in response to overload currents causing said bimetal element to release said operating means.

7. A circuit breaker having means releasable to cause automatic opening of said breaker, a trip device comprising a bimetal element formed from a single strip of bimetallic material and having a reverse bend about a transverse axis parallel to its faces to form a loop, means connecting a portion only of said bimetal element in the circuit of the breaker to be heated by the current of the circuit, means securing one leg of said bimetal element to a fixed member, means at the other leg of said bimetal element for initiating release of said releasable means, and the high and low expansion sides of said bimetal element being so arranged that the legs of said bimetal element move relative to each other in response to changes in ambient temperature to compensate said trip device.

8. In a circuit breaker having relatively movable contact means and operating means releasable to effect opening of said contact means, a trip device comprising a single U-shaped bimetal element normally restraining said operating means, said bimetal element having legs of unequal length, said bimetal element being electrically connected in the circuit of the breaker so that only a portion thereof is heated by the current of the circuit, said bimetal element having the high expansion side on the outside of the U, means securing one leg of said bimetal element to a fixed member, means at the other leg of said bimetal element for initiating release of said operating means, and the legs of said bimetal element moving in opposite directions in response to changes in ambient temperature to compensate said trip device for changes in ambient temperature.

9. A circuit breaker having means releasable to cause automatic opening of said breaker, a trip device comprising a bimetal element formed from a single strip of bimetallic material having a reverse bend about a transverse axis parallel to its faces to form a loop, said bimetal element having the high expansion side on the outside of said loop, means supporting one leg of said bimetal element, latch means operable by the other leg of said bimetal element for effecting release of said releasable means, means connecting a portion only of said bimetal element in the circuit of the breaker to be heated by the current of the circuit, said heated portion of said

bimetal element when heated by overload currents deflecting and causing said latch means to release said releasable means, and the legs of said bimetal element moving relative to each other in response to changes in ambient temperature to compensate said trip device.

10. A circuit breaker having separable contact means and operating means releasable to cause separation of said contact means, a trip device for effecting release of said operating means comprising a single bimetal element having a reverse bend about a transverse axis parallel to its faces to form a loop having legs of unequal length, the high expansion side of said bimetal element being on the outside of said loop, support means supporting the longer leg of said bimetal element, latch means operable by the shorter leg of said bimetal element cooperating with said operating means to releasably restrain said operating means, means electrically connecting said bimetal element in the circuit of the breaker so that a portion of the longer leg, said loop and said shorter leg are traversed by the current of

5 the circuit to be heated thereby, the current traversed portions of said bimetal element when heated by overload currents causing said loop to contract and said shorter leg to bend in a direction to disengage said latch means and release said operating means, the proportions of said legs and said loop being such that said legs deflect relative to each other in response to changes in ambient temperature to maintain a substantially constant latch overlap to thereby compensate said trip device for changes in ambient temperature.
